UNITED STATES PATENT OFFICE.

WILLIAM L. SIX, OF KANSAS CITY, MISSOURI.

OIL BURNER.

Application filed January 21, 1926. Serial No. 82,699.

My invention relates to oil burners and more particularly to an open retort burner to which oil is fed by gravity and there vaporized and mixed with air for supporting combustion, the principal object of the invention being to adapt a burner of this type for thermostatic control by eliminating the usual tendency of the burner to smoke or extinguish at low heat or when operating 10 only at pilot capacity.

It is also an object of the invention to provide a burner of this type wherein a steady and even supply of vapor may be maintained regardless of the feed.

15 In accomplishing these and other objects of the invention, I have provided improved details of structure, the preferred forms of which are illustrated in the accompanying drawings wherein:

20 Fig. 1 is a vertical, sectional perspective view of a burner embodying my invention.

Fig. 2 is a detail perspective view of the burner, showing the several parts in spaced relation.

25 Referring more in detail to the drawings, 1 designates a fire bowl comprising a concavo-convex bottom 2 and an upstanding peripheral wall 3, the latter having an outwardly and upwardly sloping edge flange 24, provided with legs 5 for supporting the fire bowl from the grate or other support in the furnace in which the burner is installed, the legs 5 being preferably integral with the fire bowl and provided with outwardly 30 extending feet 6 having threaded bosses 7 carrying screws 8 by which the fire bowl may be leveled upon its support.

Cast concentrically with the bottom of the fire bowl is an upstanding boss 9 internally 40 threaded as at 10 to receive a pipe 11 through which oil is supplied to the fire bowl, the supply pipe being provided with a control valve 12 by which flow to the burner may be regulated.

45 Located concentrically of and above the fire bowl is a vaporizing plate 13, having a ring boss 14 on its under face provided with radial ribs 15, which support the plate from the bottom of the fire bowl and space the 50 plate from the bowl to form an oil reservoir 16 and channels 17, through which oil may pass from the reservoir.

The vaporizing plate 13 is centered on the fire bowl by downwardly projecting lugs 18, 55 preferably integral with the plate and of such length and arrangement as to surround

and engage the upstanding boss 9 on the bottom of the bowl.

I have found that by maintaining a pool of oil in the reservoir and drawing supply 60 for vaporization from the pool instead of generating it in a coil or feed pipe, I am able to maintain a steadier and more uniform flame, and that by generating in a wick there is less tendency of the flame to 65 become extinguished than when drawing vapor directly from the body of oil. Consequently, I separate the reservoir from the combustion chamber by the vaporizing plate 13 and insulate the vaporizing plate by a 70 plate 19 of substantially the same diameter as the vaporizing plate and spaced therefrom by a downturned edge flange 20 on the insulating plate to maintain a dead air space 75 21 between the plates.

The insulating plate 19 is centered on the vaporizing plate by a boss 22 cast integral with the vaporizing plate and received in an opening 23 in the center of the insulating plate.

80 The wick before referred to constitutes a ring 24 which lies on the bottom of the fire bowl close about the edge of the vaporizing plate to receive oil or vapor flowing out through the channels 17, or by capillary attraction from the reservoir 16.

The burner is enclosed by a ring 25 supported on a ring plate 26 carried by the furnace grate (not shown) and spaced from the fire bowl to provide an air passageway 85 27, the ring being notched, as at 28, to receive the supporting legs 5 of the fire bowl, maintain the ring in position and permit it to rest firmly upon its support.

In order that combustion supporting air 90 may be delivered from the passageway 27 downwardly and in a thin layer over the wick, I provide a deflecting ring 29 which is supported from a flange 30 cast on the inner surface of the ring, near its upper edge, the ring being provided with a downwardly and inwardly sloping flange 31 which is spaced from the fire bowl flange 4 to provide a Venturi outlet 32 so that air passing through the Venturi outlet not only mixes with the vapor to form a proper feed mixture, but also drives the flame to the center of the fire bowl, insuring a thorough commingling of the air and vapor.

100 The burner is covered by a plate 33, preferably of refractory material and supported centrally over the top of the fire bowl by

legs 34 which are preferably integral with the plate and rest upon bosses 35 on the air throat ring 29.

The air outlet throat may be adjusted to vary the volume of air admitted to the burner by regulating set screws 36, which are threaded through the ring 29 and bear upon the flange 30, so that the ring may be raised and lowered to vary the width of the throat.

The fire bowl may be provided with an overflow outlet 37, preferably formed in the flange 4 slightly above the normal level of the oil in the reservoir and the oil carried off through a pipe 38 that is screwed into the flange in line with the outlet 37.

While I have shown a manually operable valve 12 for controlling supply of oil to the reservoir, it is apparent that a thermostatically controlled valve may be substituted without departing from the spirit of my invention.

In assembling the burner, the air throat ring 28 is placed over the grate in the furnace so that air may be supplied to the burner through its central opening. The fire bowl is then positioned on the plate 26 and the screws 8 adjusted to level the bowl. After the fire bowl has been leveled, the vaporizing plate 13 is placed therein with the lugs 18 engaging the boss 9 on the floor of the bowl. The insulating plate 19 is then placed on top of the vaporizing plate and the wicking placed about the periphery of the vaporizing plate to cover the outlet from the reservoir. The ring 25 may then be slipped over the fire bowl with its slotted portions engaging the feet of the fire bowl legs. The deflecting ring 29 is then positioned inside of the ring 25 and the screws 36 manipulated to adjust the air opening. The flame spreading plate 33 is positioned over the burner with the supporting legs resting on the bosses of the deflecting ring.

When the burner is operated, the valve 12 is opened, permitting oil to flow by gravity into the fire bowl until it reaches a level about midway of the horizontal diameter of the wick. A lighted paper is then placed on top of the insulating plate 19 to ignite

the oil in the wick, the wick taking up oil from the reservoir by capillary attraction to replace that which is consumed. After the vaporizing plate has become heated, vaporization takes place in the space beneath the plate and escaping through the circular outlet and wick, contacts with the incoming air to form a combustible fuel mixture. This mixture being ignited, the flame converges toward the center of the burner, and then, striking the plate 33, is spread outwardly against the walls of the furnace, the deflection insuring a mixture of the fuel elements and substantially complete combustion.

When the space served by the burner has been heated to the desired temperature, the valve 12 may be closed to reduce flow of oil to the burner, or sufficiently to discontinue vaporization by the vaporizing plate. In the latter event, the oil is burned directly from the wick with a short flame which serves as a pilot light to keep the vaporizing plate sufficiently hot to insure immediate vaporization when the valve 12 is again opened to admit a greater supply of oil, the wick ring stabilizing the pilot flame and insuring against its extinguishment by the incoming air or irregularity of flow while the burner is at a low heat.

Thus it will be seen that the burner may operate with a pilot flame small enough to prevent overheating in mild weather, but sufficient for maintaining vaporization, and without smoking.

What I claim and desire to secure by Letters Patent is:—

An oil burner comprising a bowl adapted for containing oil in fluid state, means for delivering oil to the bowl, a plate covering the bowl and spaced therefrom at its periphery to provide a restricted outlet, a heat insulating plate above the covering plate for retarding vaporization of contents of the bowl, a wick adjacent the outlet, and means for directing air over the wick to support combustion.

In testimony whereof I affix my signature.

WILLIAM L. SIX.
